RAILWAY TRAFFIC RECORDING APPARATUS**Ira F. Cadman, St. Louis, Mo., assignor to Westinghouse Air Brake Company, a corporation of Pennsylvania****Application April 4, 1951, Serial No. 219,183****10 Claims. (Cl. 246—107)**

My invention relates to railway traffic recording apparatus. More particularly, my invention relates to apparatus for recording traffic movements over a plurality of railway tracks interconnected by switches which can be arranged for setting up various traffic routes.

It is common practice to provide lamps in a track model for showing a leverman or dispatcher the positions of switches and the indications of signals and also the occupied and unoccupied conditions of sections of track at any given time. It is also common practice to provide a record, by means of a train chart or record sheet, which shows the train movements that have been made over a given stretch of single track railway during any given period.

It has been recognized for some time that there would be various advantages in having also a record of the movements of trains over a plurality of railway tracks interconnected by switches which can be arranged to form various routes over the plurality of tracks such, for example, as track layouts with which interlocking plants are used. Such a record would be useful in the making of traffic studies for determining upon more efficient use of the track layout, and in connection with the preparation of timetables. It would also serve as a check upon the character of each traffic movement, and would serve as a disciplinary check on the trainman.

An object of my invention, therefore, is the provision of means for recording each traffic movement to show the route traversed over a track layout which embodies a plurality of interconnected railway tracks.

Another object of my invention is to control the recording means to show the direction of each traffic movement over the corresponding route.

Still another object of my invention is to control the recording means to show the time of entrance onto and departure of a train or other railway vehicle from each route.

Another object of my invention is to provide a distinctive record to show when a train has "overrun" a stop signal, that is, to show when any of the wheels of a train, such for example as the front wheels of its locomotive, have moved onto a route past a signal which is displaying a stop indication.

Features of my invention for accomplishing these objects include the use of three-position marking devices or pens for making the records on a train chart or record sheet; route relays controlled by signal route check network relays and by track and switch indication relays to become energized when a train enters a route while a signal for the route is controlled to display a proceed indication; train graph relays controlled by the route relays and by track indication relays; and control circuits for the three-position pens controlled by the train graph relays and by the route relays and by the track and switch indication relays.

I shall describe one form of apparatus embodying my invention, and shall then point out the novel features thereof in claims.

The accompanying drawings, Figs. 1a, 1b, 1c, 1d and 1e, when placed side by side in the order named, with Fig. 1a on the left, constitute a diagrammatic view showing one form of apparatus embodying my invention, in which route check network circuits for signals include contacts of track circuit stick relays; in which route relays are controlled by route check stick relays and by track and switch indication relays; in which train graph relays are controlled by the route relays and by track indication relays; and in which three-position train graph pens are controlled by the train graph relays and by track and switch indication relays and also by the route relays, for recording, on a train graph or record sheet, each traffic movement over each of a given plurality of interconnected railway traffic routes, to show the direction of each traffic movement, and the time of entrance of each traffic movement onto, and the time of its departure from, any of the given plurality of traffic routes, and also at times to provide a distinctive indication if a train passes a stop signal onto one of the given routes.

Referring further to the drawings, a track plan is shown in Figs. 1a and 1b, in which two main railway tracks are interconnected, by a crossover track, through switches designated by the reference characters A1 and B1, and in which one of the main tracks is also connected with an auxiliary track by a single switch, designated by the reference character 3. Various routes can be set up over these tracks by varying the positions of the crossover switches A1 and B1 and of the single switch 3. In order to simplify the drawings, each track, comprising two parallel series of track rails, is represented by a single line.

Traffic movements in opposite directions over the various routes are governed by signals, designated by the reference characters 2R and 4R for movements from left to right, as shown in the drawings, which I shall assume is the eastbound direction, and by signals, designated by the reference characters 2LA, 2LB and 4L for movements in the opposite or westbound direction. The signals may be of any suitable design such, for example, as the well-known searchlight type.

The tracks are divided into sections, by insulated joints designated by the reference character 5. A first section, designated by the reference character 1T, extends between signals 4R and 4L; a second section, designated by the reference character 2T, extends between signal 2R and a point between switches B1 and 3, and a third section, designated by the reference character 3T, extends between section 2T and signals 2LA and 2LB. These sections are known as switch sections or detector sections. Other sections known as approach sections, designated by the reference characters 2LT, 2RT, 4LT and 4RT, are in the rear of signals 2R, 2LA, 4R and 4L, respectively. Each of the track sections is provided with a track circuit including a suitable source of current such, for example, as a battery, designated by the reference character 6, connected across the rails adjacent one end of the section, and a track relay, designated by the reference character R preceded by the reference character for the section, connected across the rails adjacent the opposite end of the section.

Contacts of the track relays are shown apart from the symbols for the relays by which they are operated. Each such contact is designated by a number placed adjacent the contact, in conjunction with the reference character for the relay, by which it is operated, placed above the contact.

Switches A1, B1 and 3 are operated to their normal positions in which they are shown in the drawings or to the opposite or reverse positions by mechanisms designated by the reference characters A1M, B1M and 3M, respectively.

Switch control circuits for controlling mechanisms A1M and B1M to move switches A1 and B1 to normal and reverse extreme positions are controlled by a manually operable control device such, for example, as a switch lever, designated by the reference character 1V, when lever 1V is placed in normal and reverse positions, designated by the reference characters *n* and *r*, respectively. The control circuits for switch mechanisms A1M and B1M are also controlled in part by a front contact which is closed by a switch locking relay, designated by the reference character 1LR, while the switch locking relay is in an energized condition. Switch mechanism 3M is controlled, similarly to mechanisms A1M and B1M, by a manually operable control device such, for example, as a switch lever, designated by the reference character 3V, and by a switch locking relay, designated by the reference character 3LR.

Switch circuit controller contacts, designated by the reference characters 21 and 24, are operated in conjunction with switches A1 and 3, respectively, and are closed in normal and reverse positions according as switches A1 and 3 are in the normal or reverse position, respectively. A switch circuit controller contact, designated by the reference character 22, is operated in conjunction with switch B1, so as to be closed only while switch B1 is in the reverse position. Another switch circuit controller contact, designated by the reference character 23, is also operated in conjunction with switch B1, and is closed only while switch B1 is in the normal position.

Normal and reverse switch indication relays, designated by the reference characters 1NWK and 1RWK, respectively, are controlled by switch circuit controller contacts 21, 22 and 23 of switches A1 and B1, so that relay 1NWK is energized while switches A1 and B1 are in the normal position, as shown in the drawings, and relay 1RWK is energized while switches A1 and B1 are in the reverse position. Normal and reverse switch indication relays, designated by the reference characters 3NWK and 3RWK, respectively, are controlled by switch circuit controller contact 24 of switch 3, so that relay 3NWK is energized while switch 3 is in its normal position, as shown in the drawings, and relay 3RWK is energized while switch 3 occupies the reverse position.

Signals 2R, 2LA, 2LB, 4R and 4L are operated in response to energization of signal mechanisms designated by the reference characters 2RG, 2LAG, 2LBG, 4RG and 4LG, respectively, for displaying a proceed indication. Energization of the signal mechanisms is controlled by the track relays and by the switch indication relays, by manually operable devices, such for example as signal control levers designated by the reference characters 2V and 4V, and also by route check stick relays, designated by reference characters 2RGS, 2LGS, 4RGS and 4LGS, which are controlled by signal route check network circuits.

Signal contacts, designated by the reference characters *g* and *y*, are operated in conjunction with each of the signal mechanisms, and are arranged so that one or the other of these contacts will be opened when the corresponding signal is controlled to display a proceed indication, but both of these contacts will be closed when the corresponding signal is displaying a stop indication.

Signal indication relays, designated by the reference characters 2RRP, 4RRP and 4LRP, are controlled by the signal contacts for signals 2R, 4R and 4L, respectively. A signal indication relay, designated by the reference character 2LRP, is controlled by the signal contacts for signals 2LA and 2LB.

Each of the route check stick relays is provided with a pickup circuit, in a signal route check network, which includes the front point of a contact of the signal indication relay for a corresponding signal. Each of the route check stick relays is also provided with a stick circuit, which includes the back point of a contact of the signal indication relay for a corresponding signal.

The signal route check network circuits also include contacts of the switch indication relays and of the switch and signal control levers, and contacts of track circuit stick relays designated by the reference characters 1TKPS and 3TKPS.

Each of the signal control levers 2V and 4V has a normal position, designated by the reference character *n*, and two control positions, designated by the reference characters *f* and *r* to the left and right of the *n* position, respectively, as shown in the drawings.

Contacts operated by the switch and signal control levers are represented on the drawings by circles, in which are placed reference characters to show the positions of the respective levers in which the contacts are closed. Contact 41 of lever 4V, for example, adjacent the left side of Fig. 1a, is closed only while lever 4V is in the *r* position, as indicated by the reference character in the circle for this contact. Contact 71 of lever 4V, an another example, is closed only while lever 4V is in the *n* or *f* position or at any point between these two positions, as indicated by the reference character *nf* in the circle for this contact.

Track circuit stick relay 1TKPS is controlled by lever 4V and by a back contact of a track indication relay 1TK. Track circuit stick relay 3TKPS is controlled by lever 2V and by a back contact of a track indication relay 3TK.

A time locking stick relay, designated by the reference character 4RASR, is controlled by relays 4RRP and 1TR and by a time element device, shown as a time element relay, designated by the reference character 4TER. Another time locking stick relay, designated by the reference character 2LASR, is controlled by relays 2LRP and 3TR, and by a time element relay, designated by the reference character 2TER.

A route locking relay, designated by the reference character 1SSR, is controlled by relays 4RASR, 2TR and 1TR, and also by a contact of lever 1V closed while lever 1V is in the *n* position. Another route locking relay, designated by the reference character 3NSR, is controlled by relays 2LASR and 3TR.

Track indication relay 1TR is controlled by a back contact of relay 1TR to become energized whenever relay 1TR becomes deenergized, and may also be controlled at times to become energized when relay 2TR or relay 3TR becomes deenergized. Track indication relay 3TK is controlled to become energized whenever either relay 2TR or relay 3TR becomes deenergized, and is also controlled to become energized at times when relay 1TR becomes deenergized.

Switch locking relays 1LR and 3LR are controlled by the route locking relays and by the track relays.

Route relays, designated by the reference characters 1SS, 3SS, 1NS and 3NS, are controlled by the route check stick relays and also by the switch indication relays and by the track indication relays.

Train graph relays, designated by the reference characters 2RX, 2LX, 4RX and 4LX, are provided with pickup circuits which are controlled by the track indication relays and by the route relays. The train graph relays are also provided with stick circuits, which are controlled by the route relays.

The various control circuits may be energized by current from any suitable source such, for example, as a battery, designated by the reference character Q, having terminals B and N, shown in Fig. 1b.

A three-position marking device such, for example, as a pen, is provided for each route end, as indicated in conjunction with the track and signal layout diagram shown in Fig. 1e. The track and signal layout diagram in Fig. 1e is for the same track and signal arrangement as the plan which is shown in Figs. 1a and 1b. Each of these pens is designated by the reference character Pen preceded by the reference character for the signal for the corresponding route end.

An operating mechanism for each of the pens is designated by the reference character P preceded by the reference character for the signal for the corresponding route end. Each of the pen operating mechanisms has a first and a second control winding designated by the reference characters rp and fp , respectively. The pen operating mechanisms are controlled by the train graph relays and by the route relays and also by the switch indication and track indication relays. Each of the pen operating mechanisms is biased by suitable means, such for example, as gravity, to a normal or median position while the pen operating mechanism is deenergized.

A train graph or record sheet is also shown in Fig. 1e. On this record sheet, the hour of the day is indicated, such, for example, as 10 A. M. Each ten-minute interval past the hour is also indicated, such, for example, as by the numerals 10, 20 and 30. The record sheet is constantly moved, by suitable means, in a direction away from the pens, which, as shown in Fig. 1e, is in the direction toward the lower edge of the drawing.

A normal or median line is marked by each pen on the train record sheet while the corresponding pen operating mechanism is deenergized. Control winding rp of each pen operating mechanism, upon becoming energized, moves the corresponding pen to a position to the right of its median line, and each control winding fp , upon becoming energized, moves the corresponding pen to a position to the left of its median line. Accordingly, as long as the control winding rp of a pen operating mechanism remains energized, the corresponding pen marks a line to the right of its median line, and as long as the control winding fp of a pen operating mechanism remains energized, the corresponding pen marks a line to the left of its median line.

The pen operating mechanisms are so controlled that, when a train moves in the eastbound direction, by any one of the various routes over the track layout shown in Fig. 1e, in response to a proceed indication displayed by a signal at the eastbound entrance end of the route, windings rp of the pen operating mechanisms for the two ends of the corresponding route will both be energized, and therefore the pens for the two ends of the route will each mark a line to the right of its median line. Similarly, when a train moves in the westbound direction by any of the various routes, in response to a proceed indication displayed by a signal at the westbound entrance end of the route, windings fp of the operating mechanisms for the two ends of the corresponding route will both be energized, and therefore the pens for the two ends of the route will each mark a line to the left of its median line.

When a train enters a route while the signals for the route are displaying stop indications, winding rp of the operating mechanism for the pen for the west end of the route will be energized, and winding fp of the operating mechanism for the pen for the east end of the route will be energized. The pen for the west end of the route will therefore mark a line to the right of its median line, and the pen for the east end of the route will mark a line to the left of its median line. A distinctive record is thus made to show that a train "overran a stop signal," that is, that the train entered a corresponding route while the signals for the route were displaying the stop indication.

Having described, in general, the arrangement and controls of the apparatus shown by the accompanying drawings, I shall now describe, in detail, its operation.

As shown by the drawings, all parts are in the normal condition, that is, all switches are in their normal position; all signals are indicating stop; all track sections are unoccupied, and therefore all track relays are energized; each of the levers 1V, 2V, 3V and 4V is in its normal position n ; relays 1NWK, 3NWK, 1LR, 3LR, 4RASR, 2LASR, 1SSR, 3NSR, 2RRP, 2LRP, 4LRP and 4RRP are energized; and relays 4RGS, 4LGS, 2RGS, 2LGS, 1TKPS, 3TKPS, 2TER, 4TER, 1TK, 3TK, 1SS, 3SS, 1NS, 3NS,

1RWK, 3RWK, 2LX, 4LX, 2RX and 4RX, and the train graph pen mechanisms are deenergized.

The circuit by which relay 4RRP is energized passes from terminal B, through contacts y and g of signal 4R, and the winding of relay 4RRP in multiple with a resistor t to terminal N. Relays 2RRP and 4LRP are energized by circuits which are similar to the circuit just traced for relay 4RRP. Relay 2LRP is energized by a circuit passing from terminal B, through contacts g and y of signal 2LA, and the winding of relay 2LRP in multiple with a resistor t to terminal N.

Relay 4RASR is energized by a stick circuit passing from terminal B, through contact 7 of relay 4RRP, front point of contact 8 of relay 4RASR, and the winding of relay 4RASR to terminal N. Relay 2LASR is also energized by a stick circuit, this stick circuit passing from terminal B, through contact 11 of relay 2LRP, front point of contact 12 of relay 2LASR, and the winding of relay 2LASR to terminal N.

Relay 1LR is energized by a circuit passing from terminal B, through contact 15 of relay 3NSR, contact 16 of relay 1SSR in multiple with contact 17 of relay 1NWK, contacts 19 and 20 of relays 1TR and 2TR, respectively, and the winding of relay 1LR to terminal N. Relay 3LR is energized by a circuit which is the same as the circuit just traced for relay 1LR, except that it includes contact 18 of relay 3TR instead of contacts 19 and 20 of relays 1TR and 2TR, respectively.

Relay 1NWK is energized by a circuit passing from terminal B, through contact 21 of switch A1, closed in the normal position, contact 23 of switch B1, and the winding of relay 1NWK to terminal N. Relay 3NWK is energized by a circuit passing from terminal B, through contact 24 of switch 3, closed in the normal position, and the winding of relay 3NWK to terminal N.

Relay 1SSR is energized by a pickup circuit passing from terminal B, through contact 28 of relay 4RASR, contact 29 of lever 1V in multiple with contact 30 of relay 2TR, contact 31 of relay 1TR, and the winding of relay 1SSR to terminal N. A stick circuit is also closed for relay 1SSR, this stick circuit passing from terminal B, through contact 28 of relay 4RASR, contact 32 of relay 1SSR, and the winding of relay 1SSR to terminal N. Relay 3NSR is energized by a pickup circuit, passing from terminal B, through contact 25 of relay 2LASR, contact 26 of relay 3TR, and the winding of relay 3NSR to terminal N. A stick circuit is also closed for relay 3NSR, which is the same as the pickup circuit just traced except that it includes contact 27 of relay 3NSR instead of contact 26 of relay 3TR.

I shall assume that an eastbound train is to move past signal 4R over switch A1 in the normal position. A leverman or dispatcher will therefore move lever 4V to its r position, thereby completing a pickup circuit for the track circuit stick relay 1TKPS, this pickup circuit passing from terminal B, through contact 34 of lever 4V, the winding of relay 1TKPS, and contact 36 of relay 1TK to terminal N. Relay 1TKPS, upon becoming energized, completes its stick circuit, which is the same as the pickup circuit just traced except that it includes contact 35 of relay 1TKPS instead of contact 34 of lever 4V.

Relay 1TKPS, upon becoming energized, also completes a pickup circuit for route check stick relay 4RGS, this pickup circuit passing from terminal B, through contact 37 of relay 4LGS, contact 38 of lever 4V, contact 39 of relay 1NWK, contact 40 of lever 1V, contact 41 of lever 4V, front point of contact 42 of relay 4RRP, the winding of relay 4RGS in multiple with a resistor t , and contact 43 of relay 1TKPS, to terminal N.

Relay 4RGS, upon becoming energized, completes a pickup circuit for route relay 1SS, this pickup circuit passing from terminal B, through contact 44 of relay 4RGS, contact 45 of relay 1NWK, and the winding of relay 1SS in multiple with a resistor t to terminal N. Relay 4RGS, upon becoming energized, also completes

a circuit for energizing the mechanism 4RG of signal 4R, this circuit passing from terminal B, through contact 51 of relay 4RTR, contact 52 of relay 1NWK, contact 53 of relay 1TR, contact 54 of lever 4V, contact 54a of relay 4RGS, and mechanism 4RG to terminal N.

Signal 4R will therefore be operated for displaying a proceed indication for governing a traffic movement over the route extending from signal 4R to signal 4L. Contact y or contact g, operated in conjunction with signal 4R, will then be opened, according as signal 4R displays an approach proceed or a clear proceed indication, as selected by means not shown in the drawing. The means for selecting between the approach proceed and the clear proceed indication is not a part of my invention, and is therefore omitted, in order to simplify the drawing.

Relay 4RRP, upon thus becoming deenergized, opens, at its contact 7, the stick circuit previously traced for relay 4RASR, causing relay 4RASR to become deenergized. Contact 28 of relay 4RASR will then open the circuits previously described for relay 1SSR, causing 20 relay 1SSR to also be deenergized.

Relay 4RGS is slow releasing because of resistor t connected in multiple with its winding, and therefore contact 55 of relay 4RGS will remain closed while contact 42 of relay 4RRP is moving from its front to its back point. Relay 4RGS will then be retained in the energized condition by a stick circuit passing from terminal B, through contact 55 of relay 4RGS, back point of contact 42 of relay 4RRP, the winding of relay 4RGS in multiple with resistor t, and contact 43 of relay 1TKPS to terminal N.

If, now, the leverman or dispatcher decides to hold the eastbound train at signal 4R, he will return lever 4V to its n position, thereby opening contact 54 of lever 4V in the circuit previously traced for signal mechanism 4RG, which will then be returned to the stop position. With signal 4R again displaying the stop indication, relay 4RRP will again become energized by its circuit previously traced.

A circuit will now be completed for energizing relay 4TER, this circuit passing from terminal B, through contact 7 of relay 4RRP, back point of contact 8 of relay 4RASR, and the winding of relay 4TER to terminal N. Upon the lapse of a measured period of time, relay 4TER will close its contact 10, thereby completing a pickup circuit for relay 4RASR, passing from terminal B, through contact 7 of relay 4RRP, contact 10 of relay 4TER, and the winding of relay 4RASR to terminal N. With relay 4RASR energized, relay 1SSR will again become energized by its pickup circuit previously traced.

I shall next assume that the leverman or dispatcher again moves lever 4V to its r position, causing signal 4R to again display a proceed indication, which causes relays 4RRP, 4RASR and 1SSR to in turn become deenergized, as previously described.

When an eastbound train now enters section 1T, deenergizing relay 1TR, mechanism 4RG will become deenergized because of the opening of contact 53 of relay 1TR, and therefore signal 4R will be controlled to again indicate stop. With signal 4R again indicating stop, relay 4RRP will again be energized by its circuit previously traced. On account of relay 1TR being deenergized, the pickup circuit for relay 1SSR will be opened at another point by the opening of contact 31 of relay 1TR.

Relay 1LR will also now be deenergized because of the opening of contact 19 of relay 1TR. With relay 1LR deenergized, mechanisms A1M and B1M of switches A1 and B1 will be deenergized because of the opening of contact 56 of relay 1LR.

Relay 1TK will become energized by a circuit passing from terminal B, through contact 69 of relay 1TR, and the winding of relay 1TK to terminal N. With relay 1TK energized, a stick circuit will be completed for relay 1SS, this circuit passing from terminal B, through con-

tact 61 of relay 1TK, contact 62 of relay 1SS, and the winding of relay 1SS in multiple with a resistor t, to terminal N.

With relay 1TK energized, relay 4RX will also become energized by a pickup circuit passing from terminal B, through contact 63 of relay 1TK, contact 65 of relay 1SS, and the winding of relay 4RX to terminal N. Relay 4RX, upon becoming energized, will complete a stick circuit passing from terminal B, through contact 64 of relay 4RX, contact 65 of relay 1SS, and the winding of relay 4RX to terminal N.

Relay 1TKPS will now be deenergized because of the opening of contact 36 of relay 1TK. On account of relay 1TKPS becoming deenergized, relay 4RGS will be deenergized because of the opening of contact 43 of relay 1TKPS. With relay 4RX energized, winding rp of pen operating mechanism 4RP for 4R pen will become energized by a circuit passing from terminal B, through the front point of contact 66 of relay 4RX, contact 67 of relay 1NWK, and the winding rp of mechanism 4RP to terminal N. Also, on account of relay 4RX being energized, winding rp of operating mechanism 4LP for 4L pen will now be energized by a circuit passing from terminal B, through the front point of contact 68 of relay 4RX, and winding rp of mechanism 4LP to terminal N.

With winding rp of mechanism 4RP energized, the 4R pen will mark a line shown, for example, as line a1, to the right of its median line. Also, with winding rp of mechanism 4LP energized, the 4L pen will mark a line, shown as line c1, to the right of its median line.

The time from the beginning of the line a1 to the end of the line c1 is the period of time occupied by the train passing over the route from signal 4R to 4L. The route taken by the train, and the period of time it occupied the route, may be further indicated by the leverman or dispatcher by making a dash line 153 from the beginning of line a1 to the end of line c1. The direction of movement of the train over the route may be clearly indicated by an arrowhead on the line 153. The leverman will now return lever 4V to its n position.

When the train leaves section 1T, relay 1TR will again become energized and cause relay 1TK to again become deenergized. With relay 1TK deenergized, relay 1SS will become deenergized because its stick circuit will be opened at contact 61 of relay 1TK. Also, with relay 1TR again energized, relay 1LR will again become energized, and will close its contact 56 in the circuit for switch mechanisms A1M and B1M. With relay 1SS deenergized, relay 4RX will now be deenergized, and therefore pen operating mechanisms 4RP and 4LP will be deenergized, and the 4R pen and the 4L pen will be returned to the median line. With relay 1TR again energized, relay 1SSR will again become energized by its pickup circuit previously traced.

I shall now assume that all parts of the apparatus are again in the normal condition, as shown in the drawings, and that a westbound train is to move past signal 4L over switch A1 in the normal position. The leverman or dispatcher will therefore move lever 4V to its f position, thereby completing another pickup circuit for relay 1TKPS, which is the same as the pickup circuit previously traced for this relay except that it includes contact 33 of lever 4V instead of contact 34 of this lever.

With lever 4V in its f position, relay 4LGS will become energized by its pickup circuit passing from terminal B, through contact 70 of relay 4RGS, contact 71 of lever 4V, contact 40 of lever 1V, contact 39 of relay 1NWK, contact 72 of lever 4V, front point of contact 73 of relay 4LRP, winding of relay 4LGS in multiple with a resistor t, and contact 43 of relay 1TKPS to terminal N. With relay 4LGS energized, relay 1NS will become energized by a pickup circuit passing from terminal B, through contact 74 of relay 4LGS, and the winding of relay 1NS in multiple with a resistor t, to terminal N. With relay 4LGS energized, signal mechanism 4LG will

be energized by a circuit passing from terminal B, through contact 75 of relay 4LTR, contact 76 of relay 1TR, contact 77 of relay 1NWK, contact 78 of lever 4V, contact 78a of relay 4LGS, and mechanism 4LG to terminal N.

Signal 4L will therefore be operated to display a proceed indication, causing relay 4LRP to be deenergized. With relay 4LRP deenergized, a stick circuit will be completed for relay 4LGS, this circuit passing from terminal B, through contact 79 of relay 4LGS, back point of contact 73 of relay 4LRP, winding of relay 4LGS in multiple with a resistor t , and contact 43 of relay 1TKPS to terminal N.

When the westbound train now enters section 1T, causing relay 1TR to become deenergized, signal mechanism 4LG will be deenergized because of the opening of contact 76 of relay 1TR. With mechanism 4LG deenergized, signal 4L will again display the stop indication, and therefore relay 4LRP will again become energized by its circuit previously described. Relay 1LR will now again be deenergized because of the opening of contact 19 of relay 1TR, and therefore the operating circuits for switch mechanisms A1M and B1M will again be opened at contact 56 of relay 1LR.

With relay 1TR deenergized, relay 1TK will again become energized by the circuit previously traced. With relay 1TK energized, a stick circuit will be completed for relay 1NS, this circuit passing from terminal B, through contact 80 of relay 1TK, contact 81 of relay 1NS, and the winding of relay 1NS in multiple with a resistor t to terminal N.

With relays 1NS and 1TK energized, a pickup circuit will be completed for relay 4LX, this circuit passing from terminal B, through contact 82 of relay 1TK, contact 84 of relay 1NS, and the winding of relay 4LX to terminal N. Relay 4LX, upon becoming energized, will complete a stick circuit passing from terminal B, through contact 83 of relay 4LX, contact 84 of relay 1NS, and the winding of relay 4LX to terminal N. With relay 1TK energized, relay 1TKPS will again be deenergized, causing relay 4LGS to in turn become deenergized because of the opening of contact 43 of relay 1TKPS.

With relay 4LX energized, winding fp of mechanism 4LP for 4L pen will now be energized by a circuit passing from terminal B, through the front point of contact 88 of relay 4LX, contact 89 of relay 1NWK, and winding fp of mechanism 4LP. With winding fp of mechanism 4LP energized, 4L pen will be moved to the left of the median line, where it will mark a line $c2$. Winding fp of mechanism 4RP will also be energized by a circuit passing from terminal B, through the front point of contact 90 of relay 4LX, and winding fp of pen operating mechanism 4RP to terminal N. The 4R pen will then be moved to the left of the median line, where it will mark a line $a2$. The leverman or dispatcher will now move lever 4V to its n position.

Lines $c2$ and $a2$ marked by 4L pen and 4R pen, respectively, will show the direction of the train movement and the time it occupied in passing over the route. The route and direction taken by the train, and the time it occupied the route may be further shown by the leverman or dispatcher by marking a dash line 154 between the beginning of line $c2$ and the end of line $a2$.

When the train leaves section 1T, relay 1TR will again become energized, causing relay 1TK and, in turn, relay 1NS to become deenergized. Relay 1LR will again be energized because of the closing of contact 19 of relay 1TR, and therefore contact 56 of relay 1LR in the circuits for switch mechanisms A1M and B1M will again be closed. With relay 1NS again deenergized, relay 4LX will be deenergized, and therefore windings fp of mechanisms 4LP and 4RP will again be deenergized, and 4L pen and 4R pen will be returned to the median line.

I shall next assume that an eastbound train is to move past signal 4R over switch A1 in the normal position, and that at the same time a westbound train is to move past

signal 2LA over switches 3 and B1 in the normal position. The 4R pen and the 4L pen will therefore be moved toward the right, as previously described, for marking lines $a3$ and $c3$, respectively, similarly to the marking of lines $a1$ and $c1$, previously described.

The leverman will move lever 2V to the f position, thereby completing a pickup circuit for energizing relay 3TKPS, this circuit passing from terminal B, through contact 91 of lever 2V, winding of relay 3TKPS, and contact 94 of relay 3TK to terminal N. Relay 3TKPS, upon becoming energized, will complete a stick circuit which is the same as the pickup circuit just traced except that it includes contact 93 of relay 3TKPS instead of contact 91 of lever 2V.

Relay 2LGS will now be energized by a pickup circuit passing from terminal B, through contact 95 of relay 2RGS, contact 96 of lever 2V, contact 97 of lever 1V, contact 98 of relay 1NWK, contact 99 of relay 3NWK, contact 100 of lever 3V, contact 101 of lever 2V, front point of contact 102 of relay 2LRP, the winding of relay 2LGS in multiple with a resistor t , and contact 103 of relay 3TKPS to terminal N. With relay 2LGS energized, a pickup circuit will be completed for energizing relay 3NS, this circuit passing from terminal B, through contact 104 of relay 2LGS, contact 105 of relay 1NWK, and the winding of relay 3NS in multiple with a resistor t , to terminal N.

Signal mechanism 2LAG will now be energized by a circuit passing from terminal B, through contact 107 of relay 2LTR, contact 108 of relay 1NWK, contact 109 of relay 2TR, contact 110 of relay 3TR, contact 111 of relay 3NWK, contact 112 of relay 2LGS, contact 112a of lever 2V, and mechanism 2LAG to terminal N. Signal 2LA will therefore now be operated for displaying a proceed indication, thereby causing relay 2LRP to become deenergized. Contact 11 of relay 2LRP will therefore open the stick circuit previously traced for relay 2LASR, causing relay 2LASR to become deenergized. With relay 2LASR deenergized, relay 3NSR will be deenergized because of the opening of contact 23 of relay 2LASR. With relay 2LRP deenergized, relay 2LGS will be energized by a stick circuit passing from terminal B, through contact 113 of relay 2LGS, back point of contact 102 of relay 2LRP, winding of relay 2LGS in multiple with a resistor t , and contact 103 of relay 3TKPS to terminal N.

When the westbound train enters section 3T, relay 3TR will become deenergized, so that its contact 110 will be opened, causing signal mechanism 2LAG to become deenergized, and signal 2LA to again display the stop indication. Relay 2LRP will then again become energized. Relay 2LASR will now become energized by a pickup circuit passing from terminal B, through contact 11 of relay 2LRP, contact 13 of relay 3TR, and the winding of relay 2LASR to terminal N. Although relay 2LASR is now again energized, relay 3NSR will remain deenergized because contact 26 of relay 3TR is open in the pickup circuit for relay 3NSR. With relay 3NSR now deenergized, the circuit for relay 1LR will be opened at another point by the opening of contact 15 of relay 3NSR, and the circuit for relay 3LR will now be opened at contact 15 of relay 3NSR and also at contact 18 of relay 3TR. With relay 3LR deenergized, the circuit for mechanism 3M will be open at contact 114 of relay 3LR.

With relay 3TR deenergized, relay 3TK will now be energized by a circuit passing from terminal B, through contact 120 of relay 3TR, and the winding of relay 3TK to terminal N. With relay 3TK energized, a stick circuit will be completed for relay 3NS, this circuit passing from terminal B, through contact 121 of relay 3TK, contact 122 of relay 3NWK, and the winding of relay 3NS in multiple with a resistor t , to terminal N.

With relays 3TK and 3NS energized, relay 2LX will be energized by a pickup circuit passing from terminal B, through contact 123 of relay 3TK, contact 125 of relay 3NS, and the winding of relay 2LX to terminal N. Relay

2LX, upon becoming energized, will complete its stick circuit passing from terminal B, through contact 124 of relay 2LX, contact 125 of relay 3NS, and the winding of relay 2LX to terminal N. With relay 3TK energized, relay 3TKPS will be deenergized by the opening of contact 94 of relay 3TK in the circuit previously traced for relay 3TKPS. With relay 3TKPS deenergized, relay 2LGS will be deenergized because of the opening of contact 103 of relay 3TKPS.

Winding *fp* of mechanism 2LAP for 2LA pen will be energized by a circuit passing from terminal B, through the front point of contact 126 of relay 2LX, contact 127 of relay 1NWK, contact 128 of relay 3NWK, and winding of relay 1NWK, contact 129 of relay 2LX, and winding *fp* of mechanism 2RP to terminal N. The 2LA pen will therefore be moved to the left, and will mark a line shown as line *d1* to the left of its median line. With relay 2LX energized, winding *fp* of mechanism 2RP for the 2R pen will also be energized by a circuit passing from terminal B, through the front point of contact 129 of relay 2LX, and winding *fp* of mechanism 2RP to terminal N. The 2R pen will therefore now mark a line *b1* to the left of its median line. A dash line *156* may now be drawn from the beginning of line *d1* to the end of line *b1*, as a means of showing further the route traversed and the direction of the train movement over the route, and also the time occupied by the train in moving over the route.

From the example given of a train movement in the westbound direction over the route from signal 2LA to signal 2R at the same time that a train is moving over an eastbound route from signal 4R to signal 4L, it follows that apparatus embodying my invention provides means for recording contemporaneous movements of trains over parallel routes. The leverman or dispatcher will return lever 2V to its *n* position after the train passes signal 2LA.

When the train enters section 2T, relay 2TR will become deenergized, thereby opening the circuit for relay 1LR at another point, at contact 29 of relay 2TR. Another circuit for energizing relay 3TK will now be completed, passing from terminal B, through contact 130 of relay 2TR, and the winding of relay 3TK to terminal N.

When the train leaves section 3T, permitting relay 3TR to again be energized, relay 3TK will remain energized, by the circuit just traced through contact 130 of relay 2TR, as long as section 2T is occupied. With relays 2LASR and 3TR now again energized, relay 3NSR will again become energized by its pickup circuit previously traced. With relays 3NSR and 3TR now again energized, relay 3LR will again be energized.

When the train leaves section 2T, permitting relay 2TR to again become energized, relay 3TK will again become deenergized by the opening of contact 130 of relay 2TR. With relay 2TR again energized, relay 1LR will also again be energized. The stick circuit for relay 3NS will now be opened at contact 121 of relay 3TK. With relay 3NS deenergized, relay 2LX will again be deenergized because of the opening of contact 125 of relay 3NS. Windings *fp* of the 2LA pen and the 2R pen will therefore now be deenergized, causing these pens to be returned to the median position.

I shall now assume that an eastbound train is to move past signal 4R over switches A1, B1 and 3, all in the reverse position. The leverman will therefore move lever 1V to the *r* position, causing the mechanisms A1M and B1M to be energized by a circuit passing from terminal B, through contact 56 of relay 1LR, contact 59 of lever 1V, mechanisms A1M and B1M, and contact 60 of lever 1V to terminal N. Switches A1 and B1 will therefore now be moved to the reverse position. The leverman or dispatcher will also move lever 3V to its *r* position, thereby completing a circuit passing from terminal B, through contact 114 of relay 3LR, contact 118 of lever 3V, mechanism 3M, and contact 119 of lever 3V to terminal N. Switch 3 will therefore also be moved to the reverse position.

With switches A1 and B1 moved to the reverse posi-

tion, the circuit for relay 1NWK will be opened at contacts 21 and 23 of switches A1 and B1, respectively, and therefore relay 1NWK will be deenergized. Relay 1RWK will now be energized by a circuit passing from terminal B, through contact 21 of switch A1 in the reverse position, contact 22 of switch B1, and the winding of relay 1RWK to terminal N. With switch 3 in the reverse position, relay 3NWK will be deenergized, and relay 3RWK will be energized by a circuit passing from terminal B, through contact 24 of switch 3 in the reverse position, and the winding of relay 3RWK to terminal N.

The leverman or dispatcher will now move lever 4V to the *r* position, thereby completing a circuit, as previously traced, for energizing relay 1TKPS. A second pickup circuit will be completed for relay 4RGS, this circuit passing from terminal B, through contact 131 of relay 2LGS, contact 132 of lever 2V, contact 133 of lever 3V, contact 134 of relay 3RWK, contact 135 of relay 1RWK, contact 136 of lever 1V, contact 41 of lever 4V, front point of contact 42 of relay 4RRP, winding of relay 4RGS in multiple with a resistor *t*, and contact 43 of relay 1TKPS to terminal N. With relay 4RGS energized, relay 3SS will become energized by a pickup circuit passing from terminal B, through contact 44 of relay 4RGS, contact 137 of relay 1RWK, and the winding of relay 3SS in multiple with a resistor *t* to terminal N.

Signal mechanism 4RG will now be energized by a circuit passing from terminal B, through contact 46 of relay 3RWK, contacts 48 and 49 of relays 3TR and 2TR, respectively, contact 59 of relay 1RWK, contact 53 of relay 1TR, contact 54 of lever 4V, contact 54a of relay 4RGS, and mechanism 4RG to terminal N. Signal 4R will therefore be operated for displaying a proceed indication, causing relay 4RRP to be deenergized. This will in turn cause relay 4RASR to be deenergized. Relay 1SSR will then also in turn be deenergized.

With relays 1SSR and 1NWK now deenergized, relays 1LR and 3LR will be deenergized because of the opening of contacts 16 and 17 of relays 1SSR and 1NWK, respectively. The circuits for switch mechanisms A1M and B1M will therefore now be opened at contact 56 of relay 1LR, and the circuit for mechanism 3M will be opened at contact 114 of relay 3LR. With relay 4RRP now deenergized, relay 4RGS will be energized by its stick circuit previously described.

When the eastbound train enters section 1T, causing relay 1TR to be deenergized, mechanism 4RG will again be deenergized because of the opening of contact 53 of relay 1TR, causing relay 4RRP to be energized, as previously described. Relay 4RASR will therefore now again become energized by a pickup circuit passing from terminal B, through contact 7 of relay 4RRP, contact 9 of relay 1TR, and the winding of relay 4RASR to terminal N. Relay 1TK will now again be energized by its circuit previously traced through contact 69 of relay 1TR. With relay 1SSR deenergized, and relay 1RWK energized, relay 3TK will now be energized by a circuit passing from terminal B, through contact 69 of relay 1TR, contact 138 of relay 1RWK, contact 139 of relay 1SSR, and the winding of relay 3TK to terminal N.

Two stick circuits will now be complete for relay 3SS, the first of which passes from terminal B, through contact 140 of relay 3TK, contact 141 of relay 3SS, and the winding of relay 3SS in multiple with a resistor *t* to terminal N. The second stick circuit which is complete for relay 3SS, passes from terminal B, through contact 61 of relay 1TK, contact 149 of relay 1RWK, contact 141 of relay 3SS, and the winding of relay 3SS in multiple with a resistor *t* to terminal N.

With relays 3TK and 3SS energized, a pickup circuit will now be completed for energizing relay 2RX, this circuit passing from terminal B, through contact 142 of relay 3TK, contact 144 of relay 3SS, and the winding of relay 2RX to terminal N. Relay 2RX, upon becoming energized, completes a stick circuit passing from terminal

B, through contact 143 of relay 2RX, contact 144 of relay 3SS, and the winding of relay 2RX to terminal N. With relay 1TK energized, relay 1TKPS will be deenergized, causing relay 4RGS to again be deenergized, as previously described.

With relays 2RX and 1RWK energized, winding *rp* of mechanism 4RP for the 4R pen will now be energized by a circuit passing from terminal B, through the front point of contact 145 of relay 2RX, contact 146 of relay 1RWK, and winding *rp* of mechanism 4RP. With relays 2RX and 3RWK energized, winding *rp* of the 2LB pen will also be energized by a circuit passing from terminal B, through front point of contact 147 of relay 2RX, contact 148 of relay 3RWK, and winding *rp* of mechanism 2LBP to terminal N. The leverman will return lever 4V to the *n* position. With winding *rp* of mechanism 4RP energized, the 4R pen will be moved toward the right for marking a line *a4*, and with winding *rp* of mechanism 2LBP energized, the 2LB pen will be moved to the right position for marking a line *e1* on the train record sheet.

When the train enters section 2T, causing relay 2TR to be deenergized, the pickup circuit for relay 1SSR will be opened at another point, at contact 30 of relay 2TR which is in multiple with contact 29 of lever 1V which is now also open. Another energizing circuit for relay 1TK will now be completed, this circuit passing from terminal B, through contact 130 of relay 2TR, contact 139 of relay 1SSR, contact 138 of relay 1RWK, and the winding of relay 1TK to terminal N.

When the train leaves section 1T, permitting relay 1TR to again become energized, relay 1TK will remain energized, as long as section 2T is occupied, by the circuit just traced, including contact 130 of relay 2TR.

When the train enters section 3T, causing relay 3TR to become deenergized, the circuit for relay 3TK which includes contact 120 of relay 3TR will again be completed. Another energizing circuit for relay 1TK will now be completed which will be the same as the circuit previously traced for relay 1TK through contact 130 of relay 2TR except that it includes contact 120 of relay 3TR instead of contact 130 of relay 2TR. The circuit for relay 3LR will now be opened at another point by contact 18 of relay 3TR.

When the train leaves section 2T, permitting relay 2TR to again become energized, relay 1SSR will again become energized by its pickup circuit previously traced. With relays 1SSR, 1TR and 2TR again energized, relay 1LR will now again be energized. With relay 1LR again energized, its contact 56 will be closed in the circuits for mechanisms A1M and B1M, and therefore the leverman or dispatcher can now return switches A1 and B1 to their normal positions, if he so desires.

I shall assume further that the leverman now returns switches A1 and B1 to their normal positions by moving lever 1V to its *n* position. Relay 1RWK will therefore again become deenergized, and relay 1NWK will become energized by its circuit previously traced. With relay 1RWK again deenergized, and with relay 1TR again energized, relay 1TK will now again become deenergized. The second stick circuit previously traced for relay 3SS through contacts 61 and 149 of relays 1TK and 1RWK, respectively, will now be open, but relay 3SS will remain energized by its first stick circuit which includes contact 140 of relay 3TK.

With relay 3SS still energized, relay 2RX will remain energized by its stick circuit, previously traced, and therefore winding *rp* of mechanism 2LBP will remain energized, and the 2LB pen will continue marking line *e1* to the right of its median position. With relay 1RWK deenergized, however, contact 146 of relay 1RWK will be open, so that winding *rp* of mechanism 4RP for the 4R pen will be deenergized, and therefore the 4R pen will return to the median position and mark the line between the lines *a4* and *a5*.

I shall now assume still further that the leverman ar-

ranges for a second eastbound train to move past signal 4R over switch A1 in the normal position while the first eastbound train is still on section 3T. When the second eastbound train enters section 1T, relay 4RX will become energized, and winding *rp* of mechanism 4RP for the 4R pen will then again become energized, as first described, by the circuit which includes the front point of contact 66 of relay 4RX. Winding *rp* of mechanism 4LP will also become energized, by the circuit previously traced through the front point of contact 68 of relay 4RX. The 4R pen and the 4L pen will therefore be moved to the right of their median positions and will mark the lines *a5* and *c4*, respectively, on the train record sheet.

When the first eastbound train leaves section 3T, permitting relay 3TR to again become energized, relay 3LR will in turn also be energized, and relay 3TK will become deenergized. With relay 3TK deenergized, relay 3SS will become deenergized on account of its stick circuit through contact 140 of relay 3TK now being open. With relay 3SS deenergized, relay 2RX will now be deenergized, causing winding *rp* of mechanism 2LBP for the 2LB pen to in turn also be deenergized. The 2LB pen will therefore be moved to its median position opposite the end of line *e1*.

When the second eastbound train leaves section 1T, relay 4RX will again be deenergized, causing the 4R pen to be returned to the median position opposite the end of line *a5*, and causing the 4L pen to be returned to the median position opposite the end of line *c4*.

The leverman or dispatcher may now mark a line 157 between the beginning of line *a4* and the end of line *e1* to show further the route taken by the first eastbound train and the direction of travel over the route, and also the length of time the train occupied the route. A line 158 may be drawn between the beginning of line *a5* and the end of line *c4* to show further the route and direction of traffic of the second eastbound train, and also the time the second eastbound train occupied this route.

I shall now assume that, with all parts again in the normal condition, as shown in the accompanying drawings, a westbound train "overruns" signal 4L displaying a stop indication, that is, at least the front wheels of the engine pass signal 4L, while signal 4L is displaying a stop indication, onto section 1T, instead of the train stopping with all wheels back of signal 4L, without entering section 1T, in response to the stop indication displayed by signal 4L. With a portion of the train on section 1T, relay 1TR will be deenergized, and therefore relay 1TK will be energized by its circuit including contact 69 of relay 1TR, previously traced.

With relay 1TK energized, winding *rp* of mechanism 4RP for the 4R pen will now be energized by a circuit passing from terminal B, through the back point of contact 90 of relay 4LX, contact 150 of relay 1NS, contact 151 of relay 1TK, contact 152 of relay 1SS, back point of contact 66 of relay 4RX, contact 67 of relay 1NWK, and winding *rp* of mechanism 4RP to terminal N. The 4R pen will therefore be moved toward the right for marking a line *a6*.

Winding *fp* of mechanism 4LP for the 4L pen will now be energized by a circuit passing from terminal B, through the back point of contact 68 of relay 4RX, contact 85 of relay 1SS, contact 86 of relay 1TK, contact 87 of relay 1NS, front point of contact 88 of relay 4LX, contact 89 of relay 1NWK, and winding *fp* of mechanism 4LP to terminal N. The 4L pen will therefore be moved toward the left for marking a line *c5*.

It will be noted that the 4L pen is moved toward the left, whereas the 4R pen is moved toward the right, so that line *c5* is to the left of the median line for the 4L pen, whereas line *a6* is to the right of the median line for the 4R pen. In this way, a distinctive indication is provided to show that a train moved onto section 1T past a signal which was displaying a stop indication. It will be noted that, in the examples of operation pre-

viously described, the pens for the two ends of each route are both moved to the right or are both moved to the left, showing that the train entered the route in response to a proceed indication displayed by a signal.

As long as any portion of the westbound train, which passed signal 4L while signal 4L was displaying a stop indication, is on section 1T, relay 1TR will be deenergized, and therefore relay 1LR will also be deenergized. The leverman or dispatcher can therefore not reverse switches A1 and B1, even though he might so desire, in order to permit a train to move over these switches in the reverse position.

I have described the operation of the apparatus for a few typical traffic movements. It is believed that the operation of the apparatus for any other possible traffic movement can be readily traced from the accompanying drawings.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays, including a plurality of manually operable signal control devices one for each of said route check stick relays, including a pickup circuit for each of said route check stick relays for each of corresponding routes, each of said pickup circuits closed only if the switches in the corresponding route are in the position required for the corresponding route, each of said pickup circuits also controlled by the corresponding signal control device, and including a stick circuit for each of said route check stick relays closed only if a signal for a corresponding route is controlled to display a proceed indication while the corresponding route is unoccupied, the combination comprising, a plurality of route relays, a pickup circuit for each of said route relays controlled by means including a corresponding route check stick relay in the energized condition, a stick circuit for each of said route relays closed in response to occupancy of a corresponding route by a train, a train graph pen for each route entrance point, each of said pens having a deenergized position and a first and a second energized position, a plurality of train graph relays, a pickup circuit for each of said train graph relays closed by a corresponding route relay in its energized condition when a corresponding route becomes occupied, a stick circuit for each of said train graph relays controlled by a corresponding route relay in the energized condition, means controlled by said train graph relays in response to traffic movements in a given direction for operating the pens for corresponding routes to said first energized position, and means controlled by said train graph relays in response to traffic movements in the opposite direction for operating the pens for the corresponding routes to said second energized position.

2. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays, including a plurality of manually operable signal control devices one for each of said route check stick relays, including a pickup circuit for each of said route check stick relays for each of corresponding routes, each of said pickup circuits closed only if the switches in the corresponding route are in the position required for the corresponding route, each of said pickup circuits also

controlled by the corresponding signal control device, and including a stick circuit for each of said route check stick relays closed only if a signal for a corresponding route is controlled to display a proceed indication while the corresponding route is unoccupied, the combination comprising, a plurality of route relays, a pickup circuit for each of said route relays controlled by means including a corresponding route check stick relay in the energized condition, a stick circuit for each of said route relays closed in response to occupancy of a corresponding route by a train, a train graph pen for each route entrance point, each of said pens having a deenergized position and a first and a second energized position, a plurality of train graph relays, a pickup circuit for each of said train graph relays closed by a corresponding route relay in its energized condition when a corresponding route becomes occupied, a stick circuit for each of said train graph relays controlled by a corresponding route relay in the energized condition, means controlled by said train graph relays controlled by a corresponding route relay in the energized condition, means controlled by each of said train graph relays for operating the pens for both ends of a corresponding route to said first energized position in response to a train entering a corresponding route while a signal for governing traffic movements in a given direction over the route is displaying a proceed indication, and means controlled by each of said train graph relays for operating the pens for both ends of a corresponding route to said second energized position in response to a train entering a corresponding route while a signal for governing traffic movements in the opposite direction over the route is displaying a proceed indication.

3. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays, including a plurality of manually operable signal control devices one for each of said route check stick relays, including a pickup circuit for each of said route check stick relays closed only if the switches in the corresponding route are in the position required for the corresponding route, each of said pickup circuits also controlled by the corresponding signal control device, and including a stick circuit for each of said route check stick relays closed only if a signal for a corresponding route is controlled to display a proceed indication while the corresponding route is unoccupied, the combination comprising, a plurality of route relays, a pickup circuit for each of said route relays controlled by means including a corresponding route check stick relay in the energized condition, a stick circuit for each of said route relays closed in response to occupancy of a corresponding route by a train, a train graph pen for each route entrance point, each of said pens having a deenergized position and a first and a second energized position, a plurality of train graph relays, a pickup circuit for each of said train graph relays closed by a corresponding route relay in its energized condition when a corresponding route becomes occupied, a stick circuit for each of said train graph relays controlled by a corresponding route relay in the energized condition, and means controlled by back contacts of said train graph relays and of said route relays for operating the pen for a given end of a corresponding route to the first energized position and for operating the pen for the opposite end of the same route to the second energized position in response to a train entering the corresponding route while the signals for the route are displaying a stop indication.

4. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality

of route check stick relays, including a plurality of manually operable signal control devices one for each of said route check stick relays, including a pickup circuit for each of said route check stick relays for each of corresponding routes, each of said pickup circuits closed only if the switches in the corresponding route are in the position required for the corresponding route, each of said pickup circuits also controlled by the corresponding signal control device, and including a stick circuit for each of said route check stick relays closed only if a signal for a corresponding route is controlled to display a proceed indication while the corresponding route is unoccupied, the combination comprising, a plurality of route relays, a pickup circuit for each of said route relays controlled by means including a corresponding route check stick relay in the energized condition, a stick circuit for each of said route relays closed in response to occupancy of a corresponding route by a train, a train graph pen for each route entrance point, each of said pens biased to a normal position but operable to a second and a third position, a plurality of train graph relays, means controlled by each of said route relays when a train enters a corresponding route for energizing a corresponding train graph relay, and means controlled by each of said train graph relays in the energized condition for operating the pens for both ends of a corresponding route to said second or said third position according as the corresponding route relay is for traffic movements in a given direction or in the opposite direction.

5. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays some of which are for traffic movements in a given direction and others of which are for traffic movements in the opposite direction, including manually controllable means for energizing each of said route check stick relays preparatory to controlling a corresponding signal to display a proceed indication for traffic movements in a corresponding direction over a corresponding route, the combination comprising, a plurality of train graph relays, means controlled by each of said route check stick relays in the energized condition for energizing a corresponding train graph relay when the train enters a corresponding route, a plurality of train graph pens one for each route entrance point, each of said pens biased by gravity to a normal position but operable to a second position for traffic movements in a given direction and operable to a third position for traffic movements in the opposite direction, and means controlled by each of said train graph relays in its energized condition for operating both pens for a corresponding route to a corresponding position.

6. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays some of which are for traffic movements in a given direction and others of which are for traffic movements in the opposite direction, including manually controllable means for energizing each of said route check stick relays preparatory to controlling a corresponding signal to display a proceed indication for traffic movements in a corresponding direction over a corresponding route, the combination comprising, a plurality of train graph relays, means controlled by each of said route check stick relays in the energized condition for energizing a corresponding train graph relay when a train enters a corresponding route, means controlled by the train on the corresponding route for then retaining the corresponding train graph relay in the energized

condition until the train leaves the corresponding route, and means controlled by each of said train graph relays in its energized condition for recording the time and length of occupancy of a corresponding route by a train.

5. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays some of which are for traffic movements in a given direction and others of which are for traffic movements in the opposite direction, including manually controllable means for effecting energization of each of said route check stick relays for a traffic movement over a corresponding route in the corresponding direction and for controlling a signal for displaying a proceed indication for governing the same traffic movement, the combination comprising, a plurality of train graph pens one for each route entrance point, each of said pens occupying a normal position when deenergized but operable to a second and also a third position when energized, and means controlled by each of said route check stick relays in the energized condition and by a train entering a corresponding route for effecting operation of both the train graph pens for the corresponding route to said second or said third position according as the corresponding route check stick relay is for traffic movements in said given direction or in said opposite direction.

8. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays some of which are for traffic movements in a given direction and others of which are for traffic movements in the opposite direction, including manually controllable means for effecting energization of each of said route check stick relays for a traffic movement over a corresponding route in the corresponding direction and for controlling a signal for displaying a proceed indication for governing the same traffic movement, the combination comprising, a plurality of train graph pens one for each route entrance point, each of said pens occupying a normal position when deenergized but operable to a second and also a third position when energized, means controlled by each of said route check stick relays in the energized condition and by a train entering a corresponding route for effecting operation of both the train graph pens for the corresponding route to said second or said third position according as the corresponding route check stick relay is energized for a traffic movement in said given direction or in said opposite direction, and means controlled by a train upon entering a route while the route check stick relays for both ends of the route are deenergized for operating the pen for one end of the route to its second position and operating the pen for the opposite end of the route to its third position.

9. In railway traffic recording apparatus for a plurality of railway tracks interconnected by switches which can be arranged in normal and reverse positions to form various traffic routes and provided with a plurality of signals one for each route entrance point for governing traffic movements over said routes, including a plurality of route check stick relays some of which are for traffic movements in a given direction and others of which are for traffic movements in the opposite direction, and including manually controllable means for effecting energization of each of said route check stick relays for a traffic movement over a corresponding route in the corresponding direction and for controlling a signal for displaying a proceed indication for governing the same traffic

movement, the combination comprising, a plurality of indication control devices, means controlled by a train upon moving over any of said routes in either direction in response to energization of the route check stick relay for the same direction for the same route for energizing a corresponding one of said indication control devices, and means controlled by the corresponding indication control device in the energized condition for recording the route and the direction of movement of the train over the route.

10. In railway traffic recording apparatus for a plurality of railway tracks interconnected by switches which can be arranged in normal and reverse positions to form various traffic routes and provided with a plurality of signals one for each route entrance point for governing 15 traffic movements over said routes, including a plurality of route check stick relays some of which are for traffic movements in a given direction and others of which are for traffic movements in the opposite direction, and including manually controllable means for effecting energization of each of said route check stick relays for a traffic movement over a corresponding route in the corresponding direction and for controlling a signal for dis-
